SIGNAL DEVICE

Robert M. Miller, Philadelphia, Pa., assignor to
 Fox Products Company, Philadelphia, Pa., a
 corporation of Pennsylvania

Application December 13, 1940, Serial No. 369,968

8 Claims. (Cl. 177—7)

This invention relates to a signal device, and especially to a device of this type adapted to be employed as a "door chime." While a number of features of the invention may be useful with a variety of types of chime members, the invention is especially suitable for use with chime tubes.

More specifically, the invention is particularly concerned with a novel chime striker and actuating mechanism therefor, which is capable of use in association with one or a plurality of chime tubes.

One of the principal objects of the invention is to provide a striker mounted in a novel manner providing for improved tone quality. The improved striker and actuating mechanism also avoid chattering of the striker against the chime or chimes.

Another important object of the invention is the provision of a striker and actuating mechanism operated by electro-magnetic means, all so arranged as to provide for reliable and positive functioning on a lower voltage current supply than has been customary heretofore. In this connection it is mentioned that most, if not all, of the chime type door signals at present on the market require a current supply of upwards of 10 volts, a step-down transformer having an output at 16 volts being customarily used with the devices now on the market. Many houses, however, are equipped with a door-bell system including a step-down transformer with a 6 volt output, this being virtually standard for equipment of that type.

The improved striker and actuating mechanism of the present invention is capable of effective and reliable operation when supplied with current from the common 6 volt bell-ringing transformer.

In a two-chime installation, the invention further contemplates simple and effective means providing alternatively for the striking of one chime or for the striking of both chimes, this alternative operation being desirable so that one push-button located at one door of a house will ring one chime and another push-button located at another door will ring both chimes.

How the foregoing and other objects and advantages are achieved will appear more fully from the following description referring to the accompanying drawings, which illustrate the invention as applied to a two-chime installation, and in which—

Figure 1 is a front elevational view of the striker and actuating mechanism as associated with the upper ends of a pair of chime tubes,

certain parts being broken away and shown in section;

Figure 2 is a plan view of the mechanism shown in Figure 1, also showing certain parts broken away and shown in section;

Figure 3 is a vertical sectional view taken as indicated by the section line 3—3 on Figure 1; and

Figure 4 is a diagrammatic view illustrating the control circuit wiring for certain units employed.

The entire mechanism, including the chime tubes, is adapted to be mounted on a vertical surface such as a wall by means of a bracket 5, the upper end of which is bent outwardly as at 6 to provide a support for any suitable cover 7.

A channel frame has its web 8 secured to the bracket 5, the channel being positioned with its upper and lower flanges 9 and 10 extended horizontally. The chime tubes 11 and 12 are hung from the lower flange 10 by means of cords 13 and 14 the ends of which project through apertures formed in the tube a short distance below the upper end thereof and are knotted inside of the tube. Each cord thus provides a supporting loop adapted to engage slots 15 formed in portions of the lower frame flange 10.

A sleeve 16 is forced into the end of each chime tube, and the sleeve is cut off at an oblique angle, as indicated at 17, which is of importance in providing a good and full tone quality upon striking the chime.

In connection with the chime tubes, it may be mentioned that ordinarily the tubes would be of substantial length, only a fragment thereof being illustrated in the drawings. The tubes, moreover, would ordinarily be of different pitch.

The chime striker comprises a striker weight 18—19 carrying a ring 20 providing the effective striker surface, this ring preferably being non-metallic. Desirably, the ring is formed of wood or of hard fiber board or composition material or the like which will produce a mellow instead of a metallic tone. The striker is carried at the free end of a striker arm 21, the inner end of which is bent to channel form as at 22 to provide spaced points of engagement with a pivot member 23, which latter is pivotally mounted in suitable apertures formed in the upper and lower flanges 9 and 10 of the frame. The pivot 23 has a part 23a of increased diameter against which the arm 21 rests, thereby vertically positioning the arm. Arm 21 may either be free to rotate on the pin or the pin may be free to rotate in the frame, or both. I prefer to shape the pin at its lower end in such manner as to provide for free rotation there-

of in its aperture in the lower flange 10 of the frame. I have found that this affords minimum friction and resistance to swinging of the striker.

Attention is now called to the fact that the axis of pivot 23 for the striker is vertical, in view of which its stroke is not affected by gravity. Movement of the striker in one direction (to the left when viewed as in Figures 1 and 2) is effected by means of a spring 24 which is connected with the striker arm 21 at a point 25, the other end of the spring being attached to a bracket 26 which is readily bendable toward and away from the striker arm in order to adjust the tension of spring 24.

Movement of the striker arm in the opposite direction (to the right when viewed as in Figures 1 and 2) is effected by means of a solenoid 27. The armature 28 of this solenoid is adapted to move toward and away from the striker arm in a guide tube 29, the end wall 30 of this tube forming a stop for movement of the armature 28 toward the striker arm. The end wall 30 of the guide tube is apertured and the armature is hollowed to pass the spring 31, this spring being secured to the armature at its inner end, as indicated at 32, and to the striker arm 21 at a point adjacent the point of attachment (25) of spring 24.

Connection of the spring 31 to the armature as at 32 is of advantage since this permits employment of a relatively long spring without the necessity of mounting the entire solenoid farther from the striker arm. The characteristics and relative strength of the springs 24 and 31 will be referred to more fully hereinafter in the description of operation, although it may here be noted that energizing the solenoid 27 causes the striker 20 to swing to the right and strike chime 12, de-energizing the solenoid being accompanied by return movement of the striker 20 to engage the chime 11.

In installations where it is desired to provide for alternative actuation of the striker to engage only one of the chimes, an additional control device is employed. This device is arranged for application or removal as a unit, and includes a mounting plate 34 adapted to be secured to the lower flange 10 of the channel frame by a nut and bolt indicated at 35. This mounting plate is bent upwardly, as seen in Figure 1, and then is bent to channel form, as at 36, to provide a support for a small solenoid 37 having an armature 38 adapted to move vertically. Integrally connected with the armature 38 is a non-magnetic (for example, brass) abutment pin 39 which is adapted to be moved upwardly when the solenoid 37 is energized. In its upper position, the pin 39 projects into the path of movement of the striker arm 21, thereby providing a limiting stop so located that during movement of the striker arm 21 toward chime 12, the stroke is arrested before the chime is struck.

The upper flange 9 of the channel frame also serves to support three binding posts 40, 41 and 42 by means of which appropriate electrical connections may be made, as described below with reference to Figure 4.

In Figure 4 a transformer is indicated at T, the primary being coupled with any suitable source of current, such as the common 110 volt, 60 cycle supply line indicated at 43. The output winding of this transformer is adapted to provide a low voltage, an E. M. F. in the neighborhood of 6 volts being effective.

The actuating solenoid 27 is adapted to be en-

ergized by either one of two switches 44 and 45, for example, push-buttons located one at one door and the other at another door of a house. One pole of each of these switches is connected with one side of the transformer, the other pole of switch 44 being coupled with binding post 41, and the second pole of switch 45 being coupled with binding post 42. Binding post 40 is coupled with the other side of the output winding of the transformer.

In addition to the wiring just referred to, the mechanism of this invention includes the following as its own internal permanent wiring:

Binding post 40 is coupled with one side of solenoid 27, the other side being connected with post 42, so that actuation of switch 45 completes a circuit through solenoid 27, thereby energizing the solenoid and causing the striker to operate.

The terminal 41 is connected with one side of the solenoid 37, the other side being connected with solenoid 27. Closing switch 44, therefore, places solenoids 27 and 37 in series with each other, thereby energizing both, with the result that the abutment pin 39 is moved upwardly to arrest movement of the striker arm in its stroke toward the chime 12, the arrangement of the solenoids and the relative masses of the moving parts being such as to bring abutment 39 into position before arm 21 can effect actuation of chime 12. Upon breaking this circuit, the striker arm swings toward and strikes chime 11.

From the above it will be seen that actuation of switch 45 provides for the ringing of both chimes, one when the solenoid 27 is energized and the other when it is de-energized; and actuation of switch 44 provides for the ringing of one chime only (11).

Referring now to the springs 24 and 31, attention is called to the fact that when the solenoid 27 is de-energized, the two springs provide an equilibrium position maintaining the striker 20 close to but out of contact with the chime 11. On the other hand, when the solenoid 27 is energized, the springs 24 and 31 provide an equilibrium position such that the striker 20 is retained close to but out of contact with chime 12. This condition is secured by the employment of relatively light but long springs, and any necessary adjustment can ordinarily be made merely by bending the tab 26 constituting the fixed reaction point for spring 24. Preferably, the strength of spring 24 is noticeably less than that of spring 31.

Coupled with the characteristics of the springs mentioned just above, the invention contemplates employment of a striker weight 18-19 of fairly substantial mass, so that the inertia of the striker will carry it in either direction beyond the equilibrium position of the springs, in order to engage one or the other of the chimes. Thus, when the solenoid 27 is energized, the stroke of the striker to the right (when viewed as in Figures 1 and 2) is sufficient to carry beyond the equilibrium position of the springs and strike the chime 12, whereupon the rebound and the effect of the springs withdraws the striker sufficiently to prevent chattering. Similarly, in the stroke in the opposite direction, the inertia carries the striker beyond the equilibrium position in order to strike chime 11, after which the striker moves away from this chime to its original equilibrium position, which is the position shown in the drawings.

In considering the foregoing operation, it may be noted that it is of importance to maintain the pivot for the striker with its axis substantially

vertical, so that free movement of the striker may occur, and further so that this movement is not influenced by the action of gravity at any portion of either stroke.

The feature just mentioned is of importance in enabling operation of the device on a relatively low voltage current, such as the common 6 volt bell-ringing transformer. Another feature of importance in this connection is the arrangement of the solenoid 27 and its armature, these being such as to provide for operation with a minimum of friction, the amount of which is very much less than that encountered in many prior devices of this general type in which the armature of a solenoid was employed for direct striking of the chimes.

The device of the present invention utilizes inertia of a striker weight in order to provide a substantial blow and, therefore, a full tone.

As hereinbefore mentioned, the improved striker mechanism of the present invention also enhances tone quality and maintains this quality notwithstanding minor misalignment in the hanging of the chimes. In prior devices in which rectilinear movement of the armature of a solenoid is employed to directly strike a chime or chimes, the matter of alignment is very critical, since if the armature and chime are slightly off center, the tone quality is materially impaired. I believe that the present invention overcomes this difficulty, at least in large part, by virtue of the employment of contacting surfaces on the chime and striker which are curved about parallel axes. As a result of such curvature, the point of contact between the striker and chime always lies on a line joining the cross sectional mass centers of the chime and striker.

Contact of the striker with each chime at a point close to the upper edge of the cut-away 17 is also of importance to tone quality.

Whatever the causes, I have found that the striker mechanism of this invention materially improves the quality of tone, which quality is, moreover, maintained notwithstanding even appreciable misalignment in the hanging of the chime tubes.

I claim:

1. A signaling system including in combination with a pair of chimes or the like, a striker mounted for movement in one direction to strike one chime and in the other direction to strike the other chime, the striker being normally maintained out of contact with either chime, a solenoid for actuating the striker in one direction to strike one chime, means for actuating the striker in the other direction to strike the other chime, an abutment movable into and out of the path of movement of the striker in its travel toward one of the chimes, a solenoid for actuating said abutment, and control circuits for said solenoids one of which is adapted to simultaneously actuate both of said solenoids, and the other of which is adapted to actuate the striker-solenoid only.

2. Apparatus of the character described including in combination with a pair of chimes, a striker pivotally mounted on an upright axis for movement in one direction to strike one chime and for movement in the other direction to strike the other chime, a spring normally urging the striker in a direction toward one chime, a solenoid for moving the striker in the opposite direction toward the other chime, the striker and solenoid being interconnected by a second spring, and the two springs having such relative strength that when the solenoid is de-energized, the po-

sition of equilibrium of the striker is close to but out of contact with one of the chimes and that when the solenoid is energized the position of equilibrium of the striker is close to but out of contact with the other of the chimes, and the mass of the striker being sufficient to cause it to override the equilibrium position toward either end of its stroke upon energizing and de-energizing of the solenoid.

3. A construction in accordance with claim 8, and further incorporating a displaceable abutment adapted to arrest movement of the striker in one direction before striking the chime at the end of that stroke, and control means providing alternatively for actuation of the striker with said abutment in operative position and with said abutment displaced.

4. Apparatus of the character described including in combination with a pair of chimes, a striker of relatively substantial mass pivotally mounted to swing between said chimes about an upright axis, resilient means normally maintaining the striker in a position of equilibrium out of contact with either chime, a solenoid, and an armature connected to said resilient means, whereby movement of the striker toward one chime is effected solely through the intermedium of said resilient means by alteration of the tension thereof when the solenoid is energized to move said armature, movement of the striker in the opposite direction to strike the other chime being effected by said resilient means upon de-energization of said solenoid.

5. In apparatus for striking a chime, the combination of a striker of relatively substantial mass pivotally mounted for swinging movement about an upright axis, spring means normally maintaining the striker in a position of equilibrium out of contact with the chime, a solenoid, and an armature connected to said spring means whereby movement of the striker is effected solely through the spring means by alteration of the tension thereof when the solenoid is energized to move said armature, an abutment movable into and out of the path of movement of the striker in its travel toward one of the chimes, a solenoid for actuating said abutment, and control circuits for both of said solenoids, one of which circuits is adapted to actuate both of said solenoids simultaneously, and the other of which circuits is adapted to actuate only the striker solenoid.

6. In combination with a chime, a striker mechanism including a striker pivotally mounted for swinging movement into and out of contact with the chime, spring means adapted to set up a position of equilibrium for the striker on its pivot but with the striker out of contact with the chime, an actuating solenoid, a movable armature associated with the solenoid, and means connecting the armature and the spring means whereby movement of the armature will change the equilibrium to increase the component of the force of the spring means tending to move the striker in the direction of the chime, the striker being adapted to move by inertia on its pivot to a point beyond equilibrium in order to strike the chime.

7. In combination with a chime, a striker mechanism including a striker pivotally mounted for swinging movement into and out of contact with the chime, an actuating solenoid, an armature adapted to be moved by the solenoid, a pair of springs acting on the striker in opposition to each other, one of the springs being connected with the movable armature and said pair of springs serving to establish an equilibrium posi-

tion of the striker on its pivot when the solenoid is energized, which equilibrium position is out of contact with the chime, the mass of the striker and resilience of the springs being such that upon energizing the solenoid the striker will pivotally override said equilibrium position and strike the chime.

8. In combination with a chime, a striker mechanism including a striker pivotally mounted for swinging movement into and out of contact with the chime, an actuating solenoid, an armature adapted to be moved by the solenoid, a pair of springs acting on the striker in opposition to

each other and serving to establish an equilibrium position of the striker on its pivot out of contact with the chime, one of the springs being connected with the movable armature and providing for upsetting the spring equilibrium when the solenoid is energized in a sense causing the striker to move in a direction away from the chime, the mass of the striker and the resilience of the springs being such that upon de-energizing the solenoid the striker will pivotally override said equilibrium position and strike the chime.
